UNITED STATES PATENT OFFICE.

CLAUDIUS DORNIER, OF FRIEDRICHSHAFEN, GERMANY.

FLYING-MACHINE CONSTRUCTION.

Application filed June 28, 1920. Serial No. 392,544.

To all whom it may concern:

Be it known that I, CLAUDIUS DORNIER, a citizen of the German Empire, residing at Friedrichshafen, Germany, have invented 5 certain new and useful Improvements in Flying-Machine Constructions, of which the following is a specification.

My invention refers to flying machines and more especially to the connection between the body or frame on the one hand and the supporting surface and the landing 10 wheels or floats on the other hand.

It is an object of my invention to simplify this connection and to secure a favorable transmission of forces from the supporting surface and the carriage or the floats, as the case may be, to the body, and vice versa, avoiding at the same time the many drawbacks connected with the usual 20 staying and bracing of the supporting surface as well as of the carriage or floats per se and relatively to the body, respectively.

With these objects and purposes in view, my invention substantially consists in a 25 novel kind of connection between the body and the carrying and supporting parts (surface, carriage, floats and the like) fixed thereto. This connection is effected substantially by hollow tubular joists, preferably 30 of sheet metal, which are fastened to the body as self-supporting members integral therewith and serve at the same time for the inner bracing of the supporting surface or the float respectively, and, in the case 35 where the carriage is concerned, directly serve as a rigid carriage. In the case of the supporting surface all staying wires or the like usually arranged between such joists can be dispensed with altogether. Moreover 40 the hollow self-supporting joists will offer passage and shelter for all kinds of steering gear and pipes and thus materially reduce the air resistance and secure an absolutely free range of vision and fire. As far as the 45 carriage is concerned, the so-called false axle as well as the usual stay wires and other braces between the single parts of the carriage are done away with. The room gained in consequence thereof can be utilized for 50 effecting a thorough connection between the joists and the body.

In the drawings affixed to this specification the preferred forms of an aeroplane provided with a wheel carriage and a hydro- 55 plane with a pair of floats are illustrated in a diagrammatic manner. In the drawings

Figs. 1 to 3 represent the aeroplane and Figs. 4 and 5 the hydroplane,
Fig. 1 being a front elevation and
Fig. 2 a side elevation, part of the body 60 being broken away, while
Fig. 3 is a similar view of a modification.
Fig. 4 is a front elevation and
Fig. 5 a side elevation, partly in section, 65 of the hydroplane.

Referring to Figs. 1 and 2 of the drawings, *a* is a body, *b*¹ are the upper forward and *b*² are the upper rear joists and *c* is the supporting surface fixed thereto. The joists *b*¹ and *b*² are hollow self-supporting sheet 70 metal tubes of approximately the shape of truncated cones and a cross-section offering the least possible resistance to the air. Near the body, and to a certain extent also near the supporting surface these conical joists 75 are dilated so as to form funnels offering large surfaces specially adapted to be connected with the body surface by screwing, riveting or welding. Pipes for cooling water, benzene or oil, steering rods, cables 80 and the like may be arranged inside said joists.

*d*¹ are the lower front and *d*² are the lower rear joists forming the carriage, said joists being formed substantially alike to the upper joists *b*¹, *b*² and fixed to the body in about the same manner. They extend in an oblique direction to both sides of the body, and the lower ends of each pair of joists *d*¹, *d*² are united to form a rest for 90 the axle *e* carrying the wheels *f*, rubber ties *g* or the like serving to keep the axle in position.

In the modification shown in Fig. 3 each pair of joists *b*¹, *b*² and *d*¹, *d*², respectively, 95 is replaced by a single joist *b* and *d* of correspondingly larger fin-like section which owing to the greater flanges available for fixation offer still greater advantages with regard to strength and transmission of forces, the free space available within these joists being so ample that they may even be braced by means of light frameworks, if desired. The lower joists have forked ends forming bearings for the axle 100 *e*, resilient buffers *h* being provided in order to absorb the shocks in landing.

The hydroplane illustrated in Figs. 4 and 5 has a pair of floats *i* fixed to the ends of the lower joists *d*₃, *d*₄. In order to avoid 110 a large exterior joint offering additional resistance to the air and in order to prevent

- the floats from turning relatively to the body the free ends of the joists are made to extend into the floats so as to form part of the inner frame-work *k* serving to stiffen them. The floats are moreover connected with each other by three horizontal bars *l* evenly distributed over their whole length. In the case where it is desired to render the floats easily replaceable, the ends of the lower joists may as well be fixed to the floats, from outside, there being no danger of the floats turning relatively to the body as long as the floats are connected with each other such as by the bars *l*.
- 15 I claim:—
1. In an aeroplane in combination, a body, self-supporting hollow joists with funnel-shaped bases fixed to said body, and starting gear attached to the lower ends of said joists.
  2. In an aeroplane in combination, a body, self-supporting hollow joists approximately shaped like truncated cones with funnel
  3. In an aeroplane in combination, a body, self-supporting hollow joists with funnel-shaped bases fixed to said body, and starting gear attached to the lower ends of said joists.
  4. In an aeroplane in combination, a body, self-supporting hollow joists with funnel-shaped bases fixed to the lower side of said body, and floats fixed to the lower ends of said joists.
  5. In an aeroplane in combination, a body, self-supporting hollow joists with funnel-shaped bases fixed to the lower side of said body, and floats fixed to the lower ends of said joists, said ends extending into the interior of said floats so as to form part of the bracing structure.

In testimony whereof I affix my signature.

CLAUDIUS DORNIER.
